US0D1110330S

(12) **United States Design Patent** (10) **Patent No.:** **US D1,110,330 S**
(45) **Date of Patent:** ** **Jan. 27, 2026**

(54) **HOLDER FOR ELECTRONIC DEVICE**

(71) Applicant: **SONY INTERACTIVE ENTERTAINMENT INC.**, Tokyo (JP)

(72) Inventor: **Naoki Ogishita**, Tokyo (JP)

(73) Assignee: **SONY INTERACTIVE ENTERTAINMENT INC.**, Tokyo (JP)

(**) Term: **15 Years**

(21) Appl. No.: **29/952,831**

(22) Filed: **Jul. 18, 2024**

(30) **Foreign Application Priority Data**

Jan. 31, 2024 (JP) ..... 2024-002009 D

(57) **CLAIM**

The ornamental design for a holder for electronic device as shown and described.

DESCRIPTION

FIG. 1 is a perspective view of front, top and right side of a holder for electronic device showing my new design; FIG. 2 is a perspective view of rear, top and left side thereof; FIG. 3 is a front view thereof; FIG. 4 is a rear view thereof; FIG. 5 is a left side view thereof; FIG. 6 is a right side view thereof; FIG. 7 is a top view thereof; FIG. 8 is a bottom view thereof; FIG. 9 is a cross-sectional view taken along line 9-9 in FIG. 3; FIG. 10 is a cross-sectional view taken along line 10-10 in FIG. 5; FIG. 11 is a first reference view showing the usage state thereof; and, FIG. 12 is a second reference view showing the usage state thereof.

The evenly spaced dashed broken lines in the figures depict portions of the holder for electronic device that form no part of the claimed design. The dash-dot broken lines depict boundaries of the claimed design and form no part thereof.
